UNITED STATES PATENT OFFICE

155,010

DESIGN FOR A DESK FILE RACK OR SIMILAR ARTICLE

Barnet D. Kaplan and Abner Weiner,
New York, N. Y.

Application April 10, 1948, Serial No. 145,634

Term of patent 7 years

(Cl. D74—3)

To all whom it may concern:

Be it known that we, Barnet D. Kaplan, a citizen of the United States, and a resident of the city of New York, in the county of Bronx and State of New York, and Abner Weiner, a citizen of the United States, residing at city of New York, Brooklyn, in the county of Kings and State of New York, have invented a new, original, and ornamental Design for a Desk File Rack or Similar Article, of which the following is a specification, reference being had to the accompanying drawing, forming part thereof.

In the drawing

Fig. 1 is a top plan view of a desk file rack or similar article, showing our new design.

Fig. 2 is a side view thereof.

Fig. 3 is an end view thereof.

Fig. 4 is end view of the opposite end thereof.

Fig. 5 is a sectional view on line 5—5 of Fig. 1, and

Fig. 6 is a sectional view thereof on line 6—6 of Fig. 1.

We claim:

The ornamental design for a desk file rack or similar article, substantially as shown.

BARNET D. KAPLAN.
ABNER WEINER.
